UNITED STATES PATENT OFFICE

FLETCHER D. GRUND, OF WESTON, OHIO, ASSIGNOR TO THE AMERICAN SWISS COMPANY,
OF TOLEDO, OHIO, A CORPORATION OF OHIO

DOOR-LATCH MECHANISM

Application filed September 17, 1928. Serial No. 306,331.

This invention relates to door latches of the type used for vehicle doors, but more particularly automobile doors, and objects are to provide a new and improved spring arrangement for yieldingly holding the latching bolt in operative position; to provide a simplified structure which lends itself to more convenient and speedy assembly without sacrificing features of strength and durability; and to provide a latch bolt having the new and improved features of construction and arrangement hereinafter described.

The invention is shown by way of illustration in the accompanying drawings, in which:

15 Fig. 1 is a top plan view of a automobile door latch;

Fig. 2 is a transverse sectional elevation on the line 2—2 of Fig. 1;

Fig. 3 is a sectional elevation on the line 20 3—3 of Fig. 1;

Fig. 4 is a sectional view on the line 4—4 of Fig. 1; and

Fig. 5 is a fragmentary view showing another method of connecting the remote 25 control link to the latching bolt.

The illustrated embodiment of the invention comprises a door latch having a mounting plate 1 provided with an upwardly bent front edge flange 2. Slidable on the mounting plate 1 is a latching bolt 3 having a part 4 extending through an opening in the flange 2. The bolt 3 is provided with an extension 5 engageable by a roll-back 6 for retracting the bolt in a well known manner. The roll-back 6 is held in place by a cover plate 7, which is individual to the roll-back, and, therefore, covers but a small part of the mounting or back plate.

40 The latching bolt 3 is formed with a longitudinally elongate slot 8, into which projects a stop member 9 struck up from the body of the mounting plate 1. For holding the latching bolt 3 in advanced or latching position, a coiled compression spring 10 is positioned within the elongate slot 8, and has one end bearing against the stop member 9 and the opposite end encircles a guide pin 11 projecting into the slot 8 from the bolt 3.

45 The convenient manner of assembling the 50 spring 10 is apparent, it merely being neces-

sary to insert one end over the guide pin 11, compress the spring slightly and push the same downwardly against the mounting plate 1. Upon releasing the spring, the opposite end will expand into engagement with the 55 stop member 9. A spring of this type is quite efficient and is advantageous also because of its cheapness.

In order to retain the spring 10 in position a keeper 12 fits over and covers the elongate slot 8. The keeper 12, in this instance, is of sheet metal and substantially in the shape of an inverted U. Formed at one end of the keeper is a pair of ears 13, which are adapted to be forced into openings 14 formed on the latching bolt 3, it being understood that the ears 13 are first brought into registration with the openings 14, forced downwardly, and then the keeper moved in a direction toward the portion 2 of the mounting plate so 60 that the ears are positioned on the under side of the latching bolt 3. This prevents outward movement of one end of the keeper. Formed on the opposite end of the keeper is a tongue 14, which is adapted to be snapped 65 into an opening 15 in the bolt 3. The tongue 14 is engaged after the ears 13 are moved into position.

In order to facilitate removal of the latching bolt 3, the mounting plate 1 is formed 70 at a side edge thereof with an elongate slot 16 open at its outer end to permit a headed pin 17 on the latching bolt 3 to be moved into engagement therewith. By this construction, the bolt is guided in its sliding movement on the mounting plate by the pin 17 cooperating with the slot 16. It will be observed that the slot 16 is directly in line with the opening through which the bolt extension 4 projects, so that the bolt is guided on the 75 mounting plate by two points of contact therewith. This provides an exceedingly simple construction without sacrificing features of strength and durability.

As is usual, the roll-back 6 is provided with 80 a projection 18, which is engaged by a dog 19, and when the parts are in engagement, the roll-back is prevented from turning. The dog 19 is, in this instance, slidable, and is provided with a pair of outwardly bent 85 90 95 100

tongues 20, which project into an elongate slot 21 formed in the mounting plate 1.

For moving the dog 19 to and from operative position, a link 22 is provided. This link may extend to a remote control arrangement, and is operable also to retract the bolt 3, the operation being such that the locking dog 19 is first retracted and subsequently the bolt. Provided on the end portion of the link 22 is a rivet 23, the head of which is disposed on the inside of an elongate slot 24 formed in the extension 5 of the latching bolt 3. A spring 25 is disposed in an opening 26 formed in the locking dog 19, and the head of the rivet 23 bears against the spring 25 so that the parts are prevented from rattling.

From the above construction, it is manifest that by moving the dog 19 to the right (Fig. 1) the same is moved into dogging position and counter-clockwise movement of the roll-back 6 is positively prevented. When the link 22 is moved to the left in Fig. 1, the dog is first moved away from the roll-back 6. When the rivet 23 reaches the end of the slot 24, further movement retracts the latch bolt 3.

As shown in Fig. 5, the link 22 may be detachable from a latch bolt 3, and is shown formed with oppositely disposed lugs 28, which may be inserted through the slot 24, and given a quarter-turn to position the lugs across the opening, and thereby prevent disengagement of the link. This enables the parts to be readily assembled and disassembled, and is particularly convenient for shipping purposes.

Numerous changes in details of construction, arrangement and operation may be effected without departing from the spirit of the invention, especially as defined in the appended claims.

What I claim as new and desire to secure by Letters Patent is:

1. In a door latch having a mounting plate and sliding latching bolt, means connecting the plate to the bolt, said means including a slot open at one end extending from one side of the plate toward the other side and a headed pin on said bolt having the shank thereof in said slot thereby to permit convenient assembly and guide the movement of the bolt.

2. A door latch comprising a back plate, a latch bolt movable over said back plate, spring means urging said bolt to latching position, a roll back for retracting said bolt, an abutment carried by and movable with said roll back, a strap longitudinally movable in the direction of movement of said bolt and disposed substantially in line with said bolt, said bolt having an apertured portion, and a combined dogging and bolt-retracting device, said device including a single actuating member fixed to and projecting at

substantially right angles from said strap toward said back plate and into said apertured portion, said apertured portion being shaped to enable movement of said device in non-bolt retracting direction when said bolt is in latching position for blocking movement of said abutment and to enable retraction of said bolt upon engagement by said actuating member with a wall of said apertured portion.

In testimony whereof I have hereunto signed my name to this specification.
